SYSTEM FOR RADIO FREQUENCY
AMPLIFICATION

Albert S. Blatterman, North Asbury Park, N. J.,
assignor, by mesne assignments, to Radio Cor-
poration of America, a corporation of Delaware

Application March 10, 1922, Serial No. 542,525

12 Claims. (Cl. 179—171)

This invention relates to radio signaling and more particularly to a method and means for receiving signals in which high frequency currents are amplified using commercial frequency alternating or varying current as a source of energy.

Heretofore in the art it has been necessary in the operation of radio frequency vacuum tube amplifiers in which a reproduction of the input variations is desired to use a source of direct current to energize or heat the filaments and to energize the plate circuits of the vacuum tubes. Suitable dry or storage batteries have been used for this purpose and considerable inconvenience has been occasioned by the necessity of charging and replacing the batteries.

My invention aims to eliminate the necessity of the use of such batteries, both for lighting the filaments and for energizing the plate circuits of the vacuum tubes by providing means whereby commercial alternating or varying currents such as the usual 110 volt 60 cycle house lighting supply, may be used to light the filaments and energize the plate circuits of the vacuum tubes in high frequency amplifiers. A further object is to provide novel means for substantially eliminating the low frequency current pulses in multi-stage amplification by suitable selection of polarity of the secondaries or primaries of the transformers used in the different stages.

Other objects are to provide novel means for maintaining a substantially zero difference of potential between the filament and grid of a vacuum tube when alternating or pulsating currents are used for heating the filaments and energizing the plate circuit, and for varying the amplifier plate circuit voltage.

Other features of my apparatus will be pointed out in the following description and shown in the drawing, in which

Figure 1 is a preferred embodiment of a receiving circuit having one stage of amplification;

Figures 2 and 3 show respectively a 4- and a 6-stage amplifier adapted to reduce or eliminate the low frequency pulses of the current;

Figure 4 is an explanatory diagram of the grid-voltage-plate-current characteristic of the amplifier.

Referring more particularly to Figure 1, there is provided an input circuit I which may be inductively connected to an antenna or other wave energy receptor in which the radio frequency voltage to be amplified originates.

A three electrode vacuum tube amplifier 1, in

combination with the suitably designed radio frequency transformer T, amplifies the radio frequency input voltage and impresses it upon an output circuit O. It will be seen that the vacuum tube 1 and the transformer T comprise one stage 5 of amplification. For further amplification similar stages are used, each comprising a vacuum tube and an output transformer. The output circuit O in each stage will be the input connection for the next stage of amplification. The 10 output circuit for the last stage of amplification comprises a detector as is usual in the art.

The filament F—1 of the vacuum tube 1 is heated by low frequency alternating or pulsating current supplied by the secondary S—2 of the 15 transformer K, the primary P of which is connected to any suitable source of low frequency alternating current supply which, for example, may be a lamp socket. The flow of current through the filament F—1 is regulated by a variable impedance R—1. To obtain a uni-directional voltage for the plate circuit of the vacuum tube 1 from the alternating current supply the secondary S—3 of the transformer K is connected to any suitable rectifier such, for instance, as the 25 vacuum tube rectifier shown.

In the method shown the secondary S—3 has one of its terminals connected to the plate and grid of a commercial type vacuum tube which are connected together as convenient means of 30 forming a two-element rectifier. A filament F—1 of vacuum tube 1 is heated by means of an alternating current derived from the secondary S—2 and may be varied by the variable impedance R—1. Connected across the filament terminals 35 of the vacuum tube 1 is the impedance R which is preferably uniformly constituted, to the mid point of which a connection E is made in such a manner that the impedances on each side of said connection are substantially equal. This 40 connection E is connected to the secondary S—3 of the transformer K and to the grid G of vacuum tube 1, this circuit including suitable means for impressing the received oscillations upon the circuit, such as the secondary I of the oscillation 45 transformer and if desired, a battery X may be used to maintain the grid at a suitable potential.

The filament of the vacuum tube 1a is heated by a low frequency alternating current supplied by the secondary S of the transformer K, and 50 is connected to the plate circuit of the vacuum tube 1. A suitable condenser C is shunted across one terminal of the secondary S—3 and the lead of the filament F—2 of the vacuum tube 1a, thus including the condenser C in the plate circuits of 55

- both tubes 1 and $1a$. When so connected the tube $1a$ will rectify the alternating voltages developed by the primary P in the secondary $S-3$ of the low frequency transformer K and cause the condenser C to accumulate a substantially uni-directional charge which may be varied at will by manipulation of the impedance $R-2$, thus varying the amplifier plate current by variation of the rectifier filament heat.
- 10 This method of obtaining a substantially direct current source of voltage from alternating supply will be recognized as one employing half wave rectification. Any satisfactory method of full wave or half wave rectification may be used instead of the one above described without deviating from the spirit of this invention. The preferred method above described has a minimum of elements and accordingly utilizes an inexpensive apparatus and is for that reason very 15 satisfactory.

It will be understood that the rectified current supplied to the plate circuit of the amplifier tube 1 is not a steady current such as that supplied by a battery or the like, but comprises a direct current component, upon which is overlaid a residual alternating ripple due to the absence of perfect smoothing out circuits or filters. However, I have discovered that when such a current is inductively transferred from one amplifying stage 20 to another by means of a suitable radio frequency transformer the effect in the output circuit, detector, or second stage is substantially eliminated.

The reason for this is that a properly designed 25 high frequency transformer has such a low impedance for low frequency currents that the voltage drop across the terminals of its secondary winding is practically negligible. Accordingly, such currents are not transferred to the secondary of the transformer and comparatively 30 large variations in the low frequency supply can be used without detrimental effect in the telephones. The amplifier tubes selected should be of such a character that their amplification is 35 inappreciably different for different values of plate energizing voltage in the neighborhood of suitable operating values of the latter and the 40 variations in plate voltage should not be permitted to exceed the values at which the amplifier 45 gives substantially constant amplification. For instance, tubes are available in which the amplification is for all practical purposes the same at 50 100 volts as at 90 volts, and no effect is therefore detected in the receiving telephones if the 55 radio frequency amplifier plate voltage is continually varied within these limits.

To further minimize the effect of a low frequency pulsating voltage applied to the plate circuit of the vacuum tube 1 , I provide the substantially uniformly constituted impedance R which is shunted across the filament $F-1$ and has its midpoint connected through the battery X to the grid G . The midpoint connection to the impedance R may be adjusted slightly to one side 60 or the other for the best operating conditions. I am enabled by this arrangement to provide a zero value of low frequency potential between the grid G and the filament $F-1$ of the vacuum tube at all times, thereby precluding all possibility of disturbance in the amplifier and eventually in the telephones which might otherwise result from variations of grid-filament potential 65 at the supply frequency. It will be understood that the impedance R is designed to be relatively 70 ineffective to low frequency currents. It will also 75

be understood that the battery X is not always necessary but may be used to set the grid-filament potential at the most suitable value for proper functioning of the amplifier.

The above connection of the input circuit I 5 to the approximate midpoint of the impedance R causes one terminal of the filament $F-1$ to be at a positive potential while the other terminal is at an equal negative potential with respect to the midpoint of the impedance R . The grid 10 G of the vacuum tube 1 is therefore simultaneously negative with respect to one terminal of the filament $F-1$ and equally positive with respect to the other. Such a condition results in the grid G which is connected to the midpoint 15 of the impedance R having at all times a potential equal to the average potential of the filament $F-1$ although a part of the filament may be negative or positive with respect to the grid. However, that portion of the filament which is 20 positive with respect to the grid can cause no electrode current flow in the grid circuit, but the portion of the filament which is negative with respect to the grid may cause a current flow which will result in variations of grid potential 25 at the supply frequency. Such voltage variation will be caused in part by drop in potential produced by the electronic current flowing through the input circuit I , and in part by the current flowing through one-half of the impedance R . The impedance of the input circuit I is necessarily very small at the filament supply frequency and accordingly produces but little 30 variation of low frequency potential across it, and since I may select an impedance R which 35 is likewise suitably small for low frequencies, the total voltage variation due to the input circuit I and the impedance R is very small for low frequencies. In actual practice I have found that such variations of grid potential as above 40 described are so extremely small as to introduce no detrimental effects in the output or detector circuit. In any case, the magnitude of the grid current which flows is extremely small on account of the characteristics of the vacuum tubes 45 and the somewhat higher voltages which are advantageously and commonly used in the plate circuits of radio frequency amplifiers. Moreover, the operation of the grid at a suitable potential causes the tube to operate on the 50 straight portion of the grid voltage-plate current characteristic so that small changes in the grid voltage due to the low frequency supply do not change its ratio of amplification and consequently do not affect the amplitude of the 55 radio frequency currents. In fact, small variations of the grid voltage operate much in the same way as small variations in the plate voltage.

The battery X may be used to provide a negative bias potential on the grid of the amplifier and by making such bias potential equal to or greater than the peak positive low frequency alternating potential developed across one-half 65 of the impedance R the grid will at no time become positive with respect to any part of the filament, and no grid current whatever will be developed, therefore low frequency variation of grid potential will be eliminated entirely.

To further describe the action of the grid circuit with alternating or pulsating direct current filament lighting, reference is made to Figure 4 illustrating the grid-voltage plate-current characteristic of an amplifier. As shown in Figure 4 70 the grid is negative with respect to the middle 75

- point of the filament by an amount equal to V_g . The grid will, therefore, be at a potential $V_g + V_f$ with respect to one end of the filament and at a potential $V_g - V_f$ with respect to the other end 5 of the filament where V_f is one-half the filament voltage. The electronic current density will, therefore, vary along the filament and the maximum ratio of the current densities at the two ends will be approximately as I_1 is to I_2 . Now 10 if the tube is operated on a straight portion of the grid-voltage-plate-current characteristic, this change of current density, varying as it does both in space and time, will produce no change in the total plate current. Dissymmetry 15 in the construction of the tube which places one end of the filament in a different geometrical relation to the grid and plate from the geometrical relation of the other end, may produce unbalancing and cause a small alternating current ripple to flow in the plate circuit. This, 20 however, may be taken care of in the same manner as a variation in the plate voltage. No modulation due to the amplifier will be produced in the output circuit so long as the extreme voltages on the grid remain inside the limits within 25 which the tube gives substantially constant amplification that is, remain within the limits of the straight portion of the grid voltage-plate current characteristic. 30 A further means for eliminating residual low frequency current ripples may be utilized in multi-stage amplification. Such a method is shown in Figures 2 and 3, which are connections for 4- and 6-stage amplifiers respectively. 35 As described with reference to Figure 1, the high frequency transformer T is extremely inefficient for currents of commercial frequencies, and accordingly such pulses are not appreciably transferred to the output circuit O . The effect, 40 however, of any residual low frequency pulses which may be transferred by the transformer T can be counteracted in the succeeding stages of the amplifier. For example, in the apparatus of Figure 2, let us assume that in the plate circuit of the first tube there is a current variation, 45 which is represented by $I \sin \omega t$. This current causes the voltage in the grid circuit of the second tube to be equal to $M_1 \omega I \cos \omega t$. This voltage on the grid of the tube causes a current in the plate circuit of the second tube which may be represented by $\alpha_2 M_1 \omega I \cos \omega t$ where α_2 is the low frequency voltage-current amplification of the second tube. This current will in turn excite in the grid circuit of the third tube a voltage equal 50 to $-\alpha_2 M_1 M_2 \omega^2 \sin \omega t I$, which will produce a current in the plate circuit of the third tube equal to $-\alpha_2 \alpha_3 M_1 M_2 \omega^2 I \sin \omega t$, in which α_3 is the amplification constant of the third tube. 55 The current ripple in the plate of the third tube, due to the alternating current source is the same as that in the first tube since all of the tubes are excited from the same alternating current source. It is seen, therefore, that any low frequency that comes from the first tube is in opposition to the low frequency in the third tube, and that these two ripples will exactly 60 counter-balance each other, provided $\alpha_2 \alpha_3 M_1 M_2 \omega^2$ is equal to 1. 65 By proper adjustment, therefore, any residual low frequency hum which passes through the radio frequency transformers can be balanced out by opposing the first stage against the third stage and the second stage may similarly be balanced against the fourth stage. Thus in any amplifier with a number of tubes which is a multi-

ple of four, any residual hum may by the use of proper constants be entirely balanced out.

In a 6-tube amplifier the residual hum may be balanced out by adding the ripple of the first and third tubes and balancing the sum against the ripple of the fifth tube. Similarly the second and fourth tubes may be added and balanced against the sixth tube. This is effected by reversing the polarity of the second transformer, as shown in Figure 3. 10

Perfect balance will be produced by establishing the following relations:

$$(\alpha_2 \alpha_3 M_1 M_2 \omega^2 + 1) \alpha_4 \alpha_5 M_3 M_4 \omega^2 = 1$$

and

$$(\alpha_3 \alpha_4 M_2 M_3 \omega^2 + 1) \alpha_5 \alpha_6 M_4 M_5 \omega^2 = 1$$

15

It is also apparent that tubes 1 and 5 may be added and balanced against tube 3 or tubes 3 and 5 against tube 1. The same combinations apply to the even numbered tubes. 20

In the case of the adding of tubes 1 and 5 and balancing against tube 3 no reversal of the transformers is necessary. In the case of adding tubes 3 and 5 and balancing against tube 1 the fourth transformer is reversed. In all of the cases the 25 reversals described also effect a balancing of the even numbered tubes.

In an amplifier with an odd number of tubes the residual hum may be balanced out for all the tubes except one. In making adjustments for 30 balance it is important to have the polarity of the transformers properly connected, otherwise the residual hum will be increased instead of being balanced out.

The foregoing analysis shows the balancing 35 out action for a disturbance of the form $I \sin \omega t$. The balancing action, however, is effective for any type of periodic function, since any such function can be decomposed into a series of the form $I \sin \omega t$. 40

It will further be understood that the variations in the plate circuits of any of the tubes may be due to voltage variation of the grid of that tube (due to alternating current heating of the filament) as well as to variations, due to the plate 45 supply. Such plate current variations due to grid voltage variations may be balanced out by the method just described.

While I have illustrated my invention in connection with a radio receiver having its local 50 circuits supplied with alternating currents of commercial frequency it will be understood that my method and apparatus is equally applicable in all cases in which it is desirable to amplify variations of one frequency and to use in the local 55 circuits current of another frequency, provided the difference in frequency between the two currents is sufficiently great to enable the apparatus to discriminate between them.

It will also be understood that the local source 60 of current need not be an alternating current, but that the method and apparatus is applicable to varying currents having variations of suitable frequency and that the frequency of the currents used in the several local circuits need not be the 65 same, provided their frequency is sufficiently different from that of the input variations it is desired to amplify. My invention also need not be taken advantage of in full, and direct current taken from batteries or another suitable source 70 may be used in some of the circuits in the place of, or in conjunction with, the alternating or varying rectifier current described. Other modifications will doubtless be evident to those skilled in the art and I therefore do not intend to con- 75

fine myself to the precise details illustrated and described.

I claim as my invention:

1. In a system of radio communication a vacuum tube multi-stage radio frequency amplifier, 5 transformers interposed between successive stages, a source of low frequency current for energizing the tubes, the transformers being so connected as to polarity that a low frequency disturbance in one stage is opposed to a corresponding low frequency disturbance in a stage separated from the stage in which the disturbance occurs by one or more stages.
- 10 2. The method of eliminating similar local disturbances of audio frequency in the several stages of a multi-stage vacuum tube amplifier which comprises opposing the disturbance of one stage against that of another stage.
- 15 3. In a multi-stage vacuum tube radio frequency amplifier in the stages of which similar audio frequency disturbances occur, means for eliminating the audio frequency disturbances comprising means for balancing the disturbances of one stage against those of another.
- 20 4. In a multi-stage radio frequency amplifier the method of eliminating similar disturbances of audio frequency in the several stages which comprises opposing the disturbances of one stage against those of a plurality of other stages.
- 25 5. In a multi-stage radio frequency amplifier the method of eliminating similar disturbances of audio frequency present in all of the stages, which comprises opposing the disturbance of one stage against that of the stage an even number 30 of stages higher than it in the order of amplification.
- 30 6. In a multi-stage radio frequency amplifier a source of audio frequency variations affecting each of the stages to substantially the same extent and means for transmitting such variations through a plurality of stages without affecting their amplitude to an extent sufficient to render it impossible to balance said audio frequency variation occurring in two of the stages against 35 one another to substantially eliminate them.
- 40 7. A signal current amplifying system employing a plurality of three-electrode vacuum tubes arranged for multi-stage amplification of a signaling current, a source of current supply for energizing a circuit of each of said tubes and tending to cause periodic disturbing variations in the plate circuit of said tubes, a coupling between the plate circuit of one of said tubes and the grid circuit of another of said tubes, said coupling being 45 so arranged that variations produced in the grid circuit by variations in the plate circuit which is coupled thereto neutralize the variations in the plate circuit of said other tube.
- 50 8. In a signal current amplifying system employing three-electrode vacuum tubes arranged for multi-stage amplification of signalling cur- 55
- 55 rent, means for energizing each of said tubes for operation from a common source of current energy tending to cause periodic disturbing variations in the plate circuits thereof, and connected to produce said variations in like phase, and means for passing to the grid circuit of one of said tubes some of the disturbing energy of another one of said tubes of phase to neutralize the disturbing variations in the plate circuit of said first tube. 10
- 60 9. In an audio frequency signal current amplifying system employing three-electrode vacuum tubes arranged for multi-stage amplification, means for energizing each of said tubes for operation from a common source of commercial alternating current energy tending to cause periodic audio frequency disturbing variations in the plate circuits thereof, and connected to produce said variations in like phase, means for transferring signal current energy and disturbing current energy from one tube to another, said means being arranged to transfer disturbing current energy of a preceding tube to neutralize disturbing current energy of a succeeding tube. 15
- 65 10. In a signal current amplifying system employing three-electrode vacuum tubes arranged for multi-stage amplification, means for energizing each of said tubes at least in part for operation from a common source of alternating current connected to said tubes so that the disturbing variations are produced in like phase, and means for passing energizing energy from one of said tubes through the grid circuit of another one of said tubes in a phase to oppose the energizing fluctuations in the plate circuit of said other tube. 20
- 70 11. A signal amplifying circuit comprising in combination a plurality of electronic tubes each thereof having input and output circuits, said tubes being arranged in cascade, a source of current supply for energizing a circuit of each of said tubes and tending to cause periodic disturbing variations in the output of the tubes, means for transferring the disturbances in one of said stages to another thereof, said means being so arranged that variations produced by said source of current supply in the one stage are neutralized by the variations in the other stage of the system. 25
- 75 12. In a signal amplifying system, a plurality of cascaded electronic tubes, means for energizing each of said tubes at least in part for operation from a common source of uni-directional fluctuating current, the source being connected to the tubes so that the fluctuating component of the energizing current is impressed in like phase and means for passing the fluctuating energy component from one of said tubes to another thereof in a phase to oppose the fluctuating component of the energizing current in the output circuit of one of said tubes. 30
